VALENTIN BORST, OF NEW YORK, N. Y.

Letters Patent No. 89,196, dated April 20, 1869.

IMPROVED HARNESS-SADDLE.

The Schedule referred to in these Letters Patent and making part of the same.

To all whom it may concern:

Be it known that I, VALENTIN BORST, of the city, county, and State of New York, have invented a new and useful Improvement in Harness-Saddles; and I do hereby declare the following to be a full, clear, and exact description thereof, which will enable those skilled in the art to make and use the same, reference being had to the accompanying drawing, forming part of this specification, in which drawing—

Figure 1 represents a plan or top view of the saddle-tree, detached.

Figure 2 is an inverted plan of the same.

Figure 3 is a longitudinal vertical section of the saddle, showing all its parts connected.

Figure 4 is a transverse section of the same.

Similar letters indicate corresponding parts.

This invention relates to a saddle-tree, which is constructed of four distinct pieces of wood, two being situated on each side of the tree, and connected together by rounded metallic corner-pieces, provided with flanges to straddle and retain the ends of the wooden side-pieces.

These wooden side-pieces are further strengthened in their position by two braces, extending across the whole width of the saddle-tree, and provided with screw-sockets, to receive and retain the terrets.

The saddle-tree is further strengthened by a metallic plate, which is secured to the inner surfaces of the metallic corner-pieces and of the wooden side-pieces, and this plate is provided with holes, to receive and retain the back-band loops.

The metallic corner-pieces of the saddle-tree are provided with sockets, to admit lugs projecting from the under surface of the cantel, and a key, passing through slots in lips projecting downward from the corner-pieces, and through corresponding slots in the lugs of the cantel, serve to fasten said cantel firmly to the tree.

The letter A designates my saddle-tree, which is constructed of four wooden side-pieces, *a a*, and two metallic corner-pieces, *b b*, the wooden side-pieces being connected in pairs by the metallic corner-pieces, shown in fig. 1 of the drawing.

Each of the metallic corner-pieces is provided with flanges, *c c*, (see fig. 3,) which overlap and straddle the ends of the wooden side-pieces, so that said side-pieces can be firmly attached to the corner-pieces.

The saddle-tree is further strengthened by metallic braces, *d*, which extend across the whole width of the side-pieces, and are provided with screw-sockets *e*, to receive and retain the terrets *f*.

By these cross-braces the two parts of the saddle-tree (each part consisting of two wooden side-pieces and a metallic corner-piece) are firmly united, and said two parts are further connected, at their under surfaces, by a base-plate, *g*, which is made of sheet-metal, and connected by means of rivets to the side and corner-pieces, shown particularly in figs. 2 and 3.

This base-plate extends beyond the side-pieces of the saddle-tree, and it is provided with holes, *h*, (see fig. 2,) to receive and retain the back-band loops *i*. This base-plate, therefore, performs the double office of connecting the side-pieces of the tree, and of retaining the back-band loops.

The metallic corner-pieces *b b* are provided with sockets, *j j*, (best seen in figs. 1 and 4,) to receive lugs *k k*, which project from the bottom surface of the cantel *B*.

And said corner-pieces are further provided with downwardly-projecting lips, or flanges, *l l*, which are perforated with slots, to receive a key, *m*, the lugs *k k* of the cantel being also provided with corresponding slots, so that by means of said key the cantel can be firmly secured to the tree.

The lips, or flanges *l l* of the metallic corner-pieces, also serve to strengthen said pieces, and to give an additional support to the wooden side-pieces.

By these means the construction of the saddle is materially simplified, and a strong and durable harness-saddle can be produced at a comparatively small cost.

Having thus described my invention,

What I claim as new, and desire to secure by Letters Patent, is—

1. A saddle-tree, composed of the wooden side-pieces *a a*, connected by the metallic flanged corner-pieces *b b*, substantially as described.

2. The cross-braces *d*, in combination with the side-pieces *a a* and corner-pieces *b b*, substantially as set forth.

3. The base-plate *g*, forming the support for the back-band loops *i*, and connected to the side-pieces *a a* and corner-pieces *b b*, substantially as described.

4. The lugs *k k*, on the cantel *B*, in combination with sockets *j j*, in the corner-pieces *b b*, and with lips, or flanges *l l*, on said corner-pieces, and with a key, *m*, substantially as set forth.

VALENTIN BORST.
